H. A. WINNE

ELECTRIC FURNACE CONTROL SYSTEM AND APPARATUS

Filed Oct. 3, 1923

Inventor:
Harry A. Winne,
by *Alexander S. Lutz*
His Attorney.

UNITED STATES PATENT OFFICE.

HARRY A. WINNE, OF SCHENECTADY, NEW YORK, ASSIGNOR TO GENERAL ELECTRIC COMPANY, A CORPORATION OF NEW YORK.

ELECTRIC-FURNACE-CONTROL SYSTEM AND APPARATUS.

Application filed October 3, 1923. Serial No. 666,242.

To all whom it may concern:

Be it known that I, HARRY A. WINNE, a citizen of the United States, residing at Schenectady, in the county of Schenectady, 5 State of New York, have invented certain new and useful Improvements in Electric-Furnace-Control Systems and Apparatus, of which the following is a specification.

This invention relates to the control of 10 electric arc furnaces and the object of my invention is to maintain the current supplied to a plurality of arcs at a predetermined relation with respect to the voltage of the arc circuit as well as to maintain the voltage 15 across the individual arcs in a predetermined relation by means of automatic electrode operating motors of simple, inexpensive and sturdy construction.

In my Patent No. 1,310,109, issued July 20 15, 1919, I have described an electric furnace control system and apparatus in which one of the furnace electrodes is operated by an electric motor controlled by electromagnetic switches and relays to correct for 25 variations of current in the arc circuit, and a second electrode is likewise operated by an electric motor controlled by electromagnetic switches and relays to correct for unbalance in the voltage drops across the two 30 electrode arcs. For large furnaces such control apparatus has proven entirely satisfactory but for smaller furnaces the initial cost of the motors, switches and relays has formed such a large proportion of the in- 35 stallation charge as to leave much to be de- sired in the way of a more simple and in- expensive automatic electrode control. My present invention contemplates a very much 40 simplified control in which all electro- magnetic switches and relays are eliminated and the electrode operating motor itself is at all times responsive to the electrical conditions of the arc circuit being controlled, whereby advantageous features of construc- 45 tion and arrangement are obtained.

In accordance with my present invention, the electrode operating motors are of the reciprocating electromagnetic type operating through a pawl and ratchet or other 50 suitable intermittent linear to intermittent rotational motion transforming mechanism to raise or lower the electrodes in a step by step manner, and each motor is provided with two opposing windings respectively 55 energized responsively to the electrical

characteristics of the arc circuit which it is desired to maintain in a predetermined relation. With the two electrical characteristics in the desired predetermined relation, the opposing windings of each electrode 60 operating motor are designed to be equally energized and hold the reciprocating armature of the motor in equilibrium. But when either of the characteristics varies from the 65 desired relation, the winding energized by the predominating characteristic operates to raise or lower one of the electrodes in a series of step by step movements until the 70 arc circuit is changed sufficiently to again bring the characteristics into the desired 75 relation.

The novel features of my invention are pointed out with particularity in the appended claims and the present preferred embodiment of my invention is illustrated 80 diagrammatically in the accompanying drawing in which, 1 represents an electric furnace of conventional form for subjecting a charge 2 to the heating action of the 85 electric arcs maintained between the pair of movable electrodes 3 and 4 and the charge, or if the charge is non-conducting, between the movable electrodes 3 and 4 and the stationary electrode 5 which is located at the 90 base of the furnace. In the form of electric furnace shown in the drawing, the two 95 arcs terminating in electrodes 3 and 4 are connected in a series circuit from supply line 8 through conductor 6, electrode 3, charge 2, electrode 4, and conductor 7 to the 100 other supply line 9. The arcing relation of electrode 3 is regulated by reciprocating electromagnetic motor 10 to maintain the current through the arc circuit in a desired relation with the voltage supplied to the 105 arc circuit from lines 8 and 9, while the arcing relation of electrode 4 is regulated by reciprocating electromagnetic motor 11 to maintain electrode 4 at the same arcing 110 distance from the charge as electrode 3.

The operating motor 10 for electrode 3 comprises a pair of armatures 12 and 13 fixed on the extremities of a connecting rod 14 and adapted to be magnetized by operating windings 15 and 16, respectively, to reciprocate the connecting rod 14 upward or downward from the mid-position in which it is shown in the drawing. At the center of connecting rod 14 a double pawl 17 is pivotally supported with the two pawl tongues 115

straddling the stationary pin 18 in such manner that one of the pawl tongues is thrown into engagement with the ratchet wheel 19 to rotate the wheel a part of a revolution in a clockwise direction when the connecting rod 14 is reciprocated by winding 15 and the other pawl tongue is thrown into engagement to rotate the wheel 19 a part of a revolution in a counterclockwise direction when the rod 14 is actuated by winding 16. The ratchet wheel 19 is mechanically connected through suitable gearing, the drawing showing a speed reducing gearing, to act on the screw threaded rod 20 to raise or lower the electrode. The gearing is shown in very diagrammatic form since the particular type of gearing is not of the essence of the invention.

Operating winding 15 of motor 10 is energized responsively to the voltage applied to the arc circuit by having one terminal connected directly to the conductor 7 as shown and the other terminal connected through the normally closed switches 21 and 23 to the other conductor 6, while winding 16 is energized responsively to the current in the arc circuit by being connected directly to the secondary of a current transformer 25 in one of the lines, line 6 as shown. Normally open switches 22 and 24 are closed during certain phases of the operation of motor 10 to short circuit winding 16. A variable resistance 26 is provided for shunting at will the secondary of the current transformer so as to calibrate the winding 16 for operation in response to any desired value of current in the arc circuit. While I have shown the winding 16 as energized from the secondary of a current transformer it will be understood that any other suitable arrangement may be provided for energizing winding 16 proportionally to the current taken by the electric furnace.

The switch 21 is pivoted at a point intermediate its ends and is biased to the closed position in any suitable manner as by means of the spring shown in the drawing. The switch 22 is also pivoted at a point intermediate its ends and is provided with a flexible contact as shown to allow continued movement of the switch after the contacts are initially closed. Switch 22 is biased to open position. These switches 21 and 22 are oppositely disposed with their operating ends in the path of and an equal distance on either side of the mid-position of finger 27 which is carried by the reciprocating connecting rod 14.

The switch 23 is shown as being of the throw-over type in which the circuit controlling blade 28 and the operating arm 29 are individually rotatable about a common pivot and are connected by the spring 30 one end of which is secured to blade 28

and the other end is secured on the opposite side of the pivot to arm 29 so that shifting the spring 30 over the pivot center by a full movement of the operating arm 29 is necessary to operate the switch blade 28 from the closed position shown to the open position in which the blade rests against the stop 31. Likewise a full reverse movement of the operating arm is also required to again operate the switch blade from the open to the closed position. For the purpose of operating switch 23, a finger 32 is located on the reciprocating connecting rod 14 in such a position that it will engage operating arm 29 and move the arm against the bias of spring 33 and shift the spring 30 over center to open the switch blade 28 near the end of the operating stroke of the connecting rod when reciprocated by winding 15. Near the end of the return stroke of the connecting rod, spring 33 serves to return operating arm 29 and shift the spring 30 over center to operate the switch blade 28 to closed position. The switch 24 is constructed the same as switch 23 just described except that it is biased to open position and is operated by finger 34 on connecting rod 14 to closed position when the connecting rod is reciprocated by winding 16.

The winding 15 of motor 10 is designed to exert an attractive force on the armature 12 when energized responsively to the normal voltage supplied to the arc circuit by lines 8 and 9 which is equal and opposite to the attractive force exerted by winding 16 on armature 13 when energized responsively to the desired current flow in the arc circuit. The connecting rod 14 is thus held in equilibrium in the central position shown, and to assist in the centering of the connecting rod under these conditions, compression springs 35 and 36 are interposed respectively between the outer ends of armatures 12 and 13 and two stationary abutments as shown. These springs center the connecting rods 14 not only when the armatures are equally attracted but also when both of the windings 15 and 16 are deenergized as will be more fully set forth in connection with the operation of my invention.

It will be observed that reciprocating electromagnetic motor 11 is essentially a duplicate of motor 10, as motor 11 has the same parts arranged in the same manner as described above with the principal exception that the operating windings are energized in a different manner. The operating winding 15' of motor 11 is energized responsively to the voltage drop across the arc terminating in electrode 4 since one terminal of the winding 15' is connected directly to the conductor 7 which connects electrode 4 to line 9 and the other terminal

is connected through switch 23', switch 21', and conductor 37 to the stationary electrode 5 which is in contact with the charge 2 in either of which all of the furnace arcs terminate. The other operating winding 16' of motor 11 is energized responsively to the voltage drop across the arc terminating in the electrode 3 by having one terminal connected directly to the conductor 8 and the other connected through switch 24', switch 22', and conductor 37 to electrode 5 and the charge 2.

Operation.

15 As thus constructed and arranged and with the parts in the respective positions shown in the drawing, the operation of my invention is as follows:

Assume that the furnace has received a suitable charge to be heated and has been connected to receive energy from the lines 8 and 9, but that the electrodes 3 and 4 have not yet been brought into arcing relation with the charge. Winding 15 of motor 10 and also windings 15' and 16' of motor 11 will be energized by the voltage across lines 8 and 9. The two windings of motor 11 are equally energized and maintain connecting rod 14 in equilibrium in the central position since they are connected in series across the lines 8 and 9 through the following circuit; from line 8 through conductor 6, winding 16', switch 24', switch 22', switch 21', switch 23', winding 15', and conductor 7 to the other line 9. Motor 11, for the time being thus remains in a balanced condition. But the winding 15 of motor 10 is energized by the voltage of the supply lines through a circuit from line 9, including conductor 7, winding 15, switch 21, switch 23, conductor 6, to the other line 8. The winding 16 is not energized since there is as yet no current flow in the arc circuit, therefore winding 15 operates to lower electrode 3 in the following manner. The armature 12 is attracted by winding 15 and moves the connecting rod 14 upwards, causing the pawl 17 to engage ratchet wheel 19 and rotate it a part of a revolution in a clockwise direction to lower electrode 3. Near the beginning of the upward stroke of connecting rod 14, the pin 27 strikes the operating end of switch 22 and moves the switch to closed position against the bias of the opening spring with which switch 22 is provided. Near the end of the upward stroke, pin 32 engages the operating arm 29 and moves the same upwards against the bias of closing spring 30 to shift the spring over center and snap the circuit controlling blade 28 into open position. This opens the energizing circuit of winding 15. Thereupon spring 35 which has been compressed by the upward stroke of the connecting rod returns the connecting rod to the central position. Switch 22 remains closed

and switch 23 remains open until the end of the return stroke of the connecting rod when both switches again are returned to their respective open and closed positions as shown in the drawing by their biasing springs. 70 The closure of switch 23 again energizes winding 15 and motor 10 operates to further rotate ratchet wheel 19 to lower electrode 3. This operation of motor 10 continues successively until electrode 3 is lowered into contact with the charge, whereupon motor 11 becomes operative to lower electrode 4 as follows:

When electrode 3 contacts with the charge 2, the operating winding 16' of motor 11 is short circuited since winding 16' is responsive to the voltage between electrode 3 and the charge 2. Winding 15' still being energized by the voltage between electrode 4 and the charge operates motor 11 in the same manner as just described for motor 10 until electrode 4 is also lowered into contact with the charge. This completes the arc circuit and causes a rush of current from the supply lines. Winding 16 of motor 10, being energized responsively to this current, attracts armature 13 thereby moving connecting rod 14 downward against the pull of winding 15 and raising electrode 3 a short distance, thus establishing an arc between the electrode 3 and the charge. Near the beginning of the downward stroke pin 27 opens switch 21 to deenergize winding 15 and remove the restraining upward pull on rod 14. Near the end of the downward stroke pin 34 engages switch 24 and operates it to closed position to short circuit and thus deenergize winding 16. Both windings 15 and 16 being deenergized, spring 36 then returns the connecting rod 14 to central position and the operation of motor 10 is repeated in this manner to raise the electrode 3 until the current in the arc circuit is reduced to the desired value at which the pull of winding 16 is equal and opposite to that of winding 15. 100 It will be observed that when both the electrodes 3 and 4 are in contact with the charge, both windings 15' and 16' of motor 11 are short circuited. As electrode 3 is raised by motor 10 as just described and an arc is established between electrode 3 and the charge, the voltage drop across this arc is impressed on winding 16' of motor 11. Winding 16' thereupon attracts armature 13' and causes the operation of motor 11 to raise electrode 4 a short distance in the same manner as winding 16 operated motor 10, thereby establishing an arc between electrode 4 and the charge, the voltage drop of which is impressed on winding 15'. Winding 16', however, continues to operate the motor 11 to raise the electrode 4 until the voltage drop across the arc terminating in electrode 4 equals that across the arc terminating in electrode 3, which condition will be ob- 120

tained when both electrodes are the same arcing distance from the charge. Then the windings 15' and 16' are equally energized and the connecting rod 14' of motor 11 is held in equilibrium.

With normal voltage and the desired current flow in the arc circuit, and the voltage drops across the arcs of electrodes 3 and 4 equal, the respective windings of motors 10 and 11 will be equally energized and maintain their respective connecting rods 14 and 14' in equilibrium in the central position. From the foregoing, it will be evident that upon a variation of either the voltage or the current of the electrode circuit from the predetermined relation in which windings 15 and 16 are equally energized, motor 10 will become operative to raise or lower electrode 3 to reestablish the balanced relation. 15

20 As pointed out above, the resistance 26 may be varied at will to change the relation between the voltage and current in the arc circuit at which the windings of motor 10 will be equally energized. Likewise upon a 25 variation from a balanced relation in the voltage drops across the arcs terminating in electrodes 3 and 4, motor 11 will become operative to raise or lower electrode 4 to re-establish the balanced relation. Although 30 I prefer to have the motor 11 maintain a balanced relation between the voltage drops of the arcs, it will be understood that should any predetermined unbalanced relation be desired, suitable variable resistance may be 35 inserted in the circuits of either or both of the operating windings 15' and 16' to permit adjustment of the voltage applied to the windings to any desired values.

In accordance with the provisions of the 40 patent statutes, I have described the principle of operation of my invention, together with the apparatus which I now consider to represent the best embodiment thereof, but I desire to have it understood that the apparatus shown is only illustrative and that the invention can be carried out by other means.

What I claim as new and desire to secure by Letters Patent of the United States, is:—

50 1. A furnace regulator comprising a reciprocating electromagnetic mechanism for operating a furnace electrode, a plurality of normally opposed operating windings for said mechanism energized responsively to different electrical characteristics of the electrode circuit, and switch mechanism and connections whereby the energization of one of said windings is varied to permit the predominating winding to change the arcing relation of the electrode when the said electrical characteristics vary from a predetermined relation.

60 2. A furnace regulator comprising a reciprocating electromagnetic mechanism for operating a furnace electrode, a pair of nor-

mally opposed operating windings therefor, each energized responsively to a different electrical characteristic of the electrode circuit, and switch mechanism and connections whereby the magnetic force of one of said windings is varied to permit the predominating force of the other winding to change the arcing relation of the electrode when the electrical characteristics of the electrode circuit vary from a predetermined relation. 70

3. A furnace regulator comprising a pawl and ratchet mechanism mechanically connected to operate a furnace electrode in successive steps in either direction, electromagnetic means having normally opposed operating 80 windings for reciprocating the pawl of said mechanism each way from a mid-position, and connections whereby the energization of the said windings is balanced in response to a predetermined relation between two different electrical characteristics of the electrode circuit.

4. A furnace regulator comprising gearing including a double acting pawl and ratchet mechanism operable in one direction to raise a furnace electrode and operable in the other direction to lower the electrode, a reciprocating operating member for the pawl biased to the mid-position, electromagnetic means for moving the said reciprocating member in either direction from the mid-position, limit switch mechanism actuated responsively to the movement of the reciprocating member, and connections whereby the energization of said electromagnetic means is controlled in response to a predetermined relation between two different electrical characteristics of the electrode circuit to operate the said electrode in successive steps. 95

5. A furnace regulator comprising a double acting pawl and ratchet operable in one direction to raise a furnace electrode and operable in the other direction to lower the electrode, a pair of opposing electromagnets 110 for operating said pawl and ratchet mechanism and connections whereby upon the energization of one of said magnets predominating the energization of both magnets is successively altered to operate said electrode 115 in a direction determined by the predominating magnet.

6. A furnace regulator comprising a double acting pawl and ratchet operable in one direction to raise a furnace electrode 120 and operable in the other direction to lower the electrode, a reciprocating operating member for the pawl biased to the mid-position, a pair of opposing electromagnets for operating said member, a plurality of limit switches actuated responsively to the movement of said reciprocating member, and connections whereby upon the energization of one of said magnets predominating the energization of both magnets is successively 125 130

altered to operate said electrode in a direction determined by the predominating magnet.

7. A regulator for an electrode adapted to be connected in circuit with a source of electrical energy to support electromagnetic mechanism having a reciprocating electric arc, comprising an armature member biased to mid-position and successively operable in one direction to move said electrode to increase the length of the arc and successively operable in the other direction to move said electrode to decrease the length of said arc, two operating windings for said armature member, one for operating said armature member in one direction responsively to an electrical characteristic of the electrode circuit, and the other for operating said armature member in the other direction responsively to another electrical characteristic of the electrode circuit, and switch mechanism and connections whereby when said electrical characteristics are in a predetermined relation said windings are equally energized to maintain said armature in equilibrium and upon a variation of one of said electrical characteristics from the said predetermined relation the predominating one of said windings is successively energized and deenergized to reciprocate said armature member from the mid-position in the direction to restore the electrical characteristic of the arc to the said predetermined relation with the other electrical characteristic of the electrode circuit.
8. A regulator for an electric arc furnace having a plurality of arcing electrodes adapted to be connected in circuit with a source of supply, comprising a plurality of reciprocating electromagnetic motors, each mechanically connected to operate a corresponding one of said electrodes and each
- having two opposing normally energized operating windings, and switch mechanism and connections whereby one winding of one of said motors is deenergized to permit operation of the corresponding electrode by the other winding upon variations from a predetermined relation between the voltage and current of said arc circuit and one winding of the second motor is deenergized to permit operation of the corresponding electrode by the other winding upon variations from a predetermined relation between the voltage drops across the respective arcs terminating in said first and second electrodes.
9. A regulator for an electric arc furnace having a plurality of arcing electrodes adapted to receive current from a source of supply, comprising a plurality of reciprocating electromagnetic motors each having two opposing operating windings which maintain the motor in equilibrium when equally energized and which effect operation of the motor in a direction determined by the predominating winding when the windings are unequally energized, each of said motors being mechanically connected to control the arcing relation of a corresponding one of said electrodes, and connections whereby one of the windings of one of the motors is energized responsively to the voltage of the source and the other winding is energized responsively to the current through one of the electrodes, and one of the windings of a second motor is energized responsively to the voltage drop across the arc controlled by the first motor and the other winding is energized responsively to the voltage drop across the arc controlled by the second motor.

In witness whereof, I have hereunto set my hand this 1st day of October, 1923.

HARRY A. WINNE.

Certificate of Correction.

It is hereby certified that in Letters Patent No. 1,551,355, granted August 25, 1925, upon the application of Harry A. Winne, of Schenectady, New York, for an improvement in "Electric-Furnace-Control Systems and Apparatus," errors appear in the printed specification requiring correction as follows: Page 5, line 6, claim 7, after the word "support" insert the words *an electric arc, comprising, and* line 7, after the word "reciprocating" strike out the words "electric arc comprising an"; and that the said Letters Patent should be read with these corrections therein that the same may conform to the record of the case in the Patent Office.

Signed and sealed this 29th day of September, A. D. 1925.

[SEAL.]

KARL FENNING,
Acting Commissioner of Patents.
